ROLLER SUPPORT FOR TURNING PIPE SECTIONS

Raymond C. Dreier, Chicago, Ill., assignor, by mesne assignments, to Dreier Brothers, Inc., Chicago, Ill., a corporation of Illinois

Application July 17, 1953, Serial No. 26,029

Term of patent 14 years

(Cl. D41—1)

To all whom it may concern:

Be it known that I, Raymond C. Dreier, a citizen of the United States, residing at Chicago, in the county of Cook and State of Illinois, have invented a new, original, and ornamental Design for a Roller Support for Turning Pipe Sections, of which the following is a specification, reference being had to the accompanying drawing forming part thereof, wherein:

Fig. 1 is a perspective view of a roller support for turning pipe sections embodying my new design;

Fig. 2 is a front elevational view thereof on an enlarged scale;

Fig. 3 is a top plan view of the support;

Fig. 4 is a bottom plan view thereof;

Fig. 5 is an end view; and

Fig. 6 is a cross-sectional view taken substantially along the line 6—6 in Fig. 2.

I claim:

The ornamental design for a roller support for turning pipe sections, substantially as shown.
